UNITED STATES PATENT OFFICE.

ALPHONSO RIGGS, OF CINCINNATI, OHIO.

NASAL INHALER.

No. 907,178.

Specification of Letters Patent.

Patented Dec. 22, 1908.

Application filed April 25, 1908. Serial No. 429,113.

To all whom it may concern:

Be it known that I, ALPHONSO RIGGS, a citizen of the United States, and residing at Cincinnati, Hamilton county, State of Ohio, have invented certain new and useful Improvements in Nasal Inhalers; and I do declare the following to be a clear, full, and exact description of the invention, attention being called to the accompanying drawing, with the reference characters marked thereon, which forms also a part of this specification.

This invention concerns improvements in the construction of inhalers adapted to be used by insertion into the nostrils and serving for treatment by medication of the nasal orifices and of the air-passages contiguous thereto and the tissues and membranes connected therewith.

My invention relates more particularly to that class of these devices where treatment is not effected by direct contact of medicated matter with the internal surfaces of the nasal-passages, but by contact with vapors merely, which are derived from evaporation of such matter and are carried in with the inhaled air.

The medicated matter it is proposed to use, usually of volatile character, is carried in a suitable receptacle adapted to be inserted and held within the nostrils in a manner to cause the air to come in intimate contact therewith while passing in, whereby such air becomes more or less impregnated with vapor emanating from such matter which is then carried into the air passages. Disinfectants may also be used in which case the device serves as a protector to physicians and nurses to prevent infection by contagion. The medicated or disinfectant matter used is frequently of a character which produces unfavorable effects when coming in direct contact with interior mucous surfaces of the nasal passages. Chemicals involving acids are sometimes used in compounding such medicated matter which by their erosive action cause irritation and are apt to set up inflammation and other complications.

The leading object of my invention is to construct such a device in a manner which permits free access of air to the medicated matter and contact therewith to obtain the

desired effect, without impeding in any way the function of breathing and further so as to prevent all possibility of contact of medicated matter with interior surfaces and tissues.

In the following specification and particularly pointed out in the claims at the end thereof, will be found a full description of my invention, together with its manner of use, parts and construction, which latter is also illustrated in the accompanying drawing, in which:

Figure 1, illustrates manner of use of the device and shows it in position within the nostrils. Fig. 2, is an enlarged top-view of the device. Fig. 3, is a transverse section of it as shown in the preceding figure. Fig. 4, is an underside view of a certain part thereof. Fig. 5, is a side-elevation of the device, with parts broken away. Fig. 6, in part of a view similar to Fig. 3, shows a modified arrangement of certain parts of the device.

The appliance consists of two flat diaphragms A, A, shaped around their edges so as to conform approximately to the shape of the nostrils and of a size to fill them, transversely considered, at the position where they occupy them and as shown in Fig. 1. This results in the curved shapes shown in Fig. 2 and produces a relation of right and left between them. At their inner, opposite edges, they are connected to each other by a bow-shaped bridge B of resilient material, preferably spring-wire, and the space between these connected edges is so arranged that they slightly impinge on opposite sides of the septum C when inserted as shown in Fig. 1, whereby the appliance is held in place. The edge of each diaphragm presents an uninterrupted, continuously smooth outline arranged and fitted to maintain contact evenly all around with the interior surface of the nostrils, thereby excluding possibility of soreness and irritation which might be caused if contact with the soft tissues were limited to separated portions only, of the edge.

D are shells which may be provided on either side of the diaphragms, that is on their upper side as shown in Figs. 1, 2, 3, and 5, or on their lower side as shown in Fig. 6. They are substantially semi-tubular

transversely considered and open on their sides towards the diaphragms, together with which they constitute the receptacles which contain the medicated matter. The shape of their outline around their edges conforms substantially to the shape of the outline of the diaphragms, both edges being parallel and spaced from each other.

Provision is made to permit free passage 10 of air in either direction necessary for breathing, for which purpose diaphragms as well as shells are each multiperforated between their edges. The openings necessary for this purpose may be small, circular orifices *d* as to the shells as shown. As to the diaphragms, they are preferably parallel slots *a a*, which results in parallel bars 7 between them, connected by shorter bars 8, as best shown in Fig. 4. It will now be 15 seen that these slotted diaphragms A, together with the perforated shells D constitute inclosures with a multiperforated wall. The medicated matter received therein may be placed directly inside in bulk-form, provided its particles are not so small as to drop through any of the openings. Usually 20 however this matter is in liquid-form, the liquid being applied to some fibrous material like cotton or sponge, which material, after 25 being saturated with such liquid, is placed 30 into the receptacles.

The size of the shells D is such that they leave a space between their edges and the edges of the diaphragms, the space being 35 by preference of a width to leave not only the outer, continuous bar 7, but also slots *a* next to it uncovered, so that, as will be seen, the receptacles are separated from the mucous membrane and tissues within the nostrils by 40 this continuous, outer bar and by the slots *a* next to it, said bar serving as a curb, or fender which holds the soft tissues away from the receptacles and prevents medicated matter coming in contact with them. 45 At the same time passage of air is not restricted and may freely pass all around between the container and the interior surface of the nostrils as shown in Fig. 1, as well as through the perforated receptacles where it 50 may take up medicated matter and carry the same inwardly.

The preferable manner of attachment of shells D to diaphragms A, is a hinged one as shown, tang-shaped portions of metal 55 which extend from one of the edges of the shells being formed into hinges 9, by being bent around one of the bars 7 of the diaphragms. The bar next to the outer bar is so used as shown in Figs. 3 and 5, so as to 60 leave the outer edges, which serve as the curbs mentioned, perfectly smooth. Two hinges are preferably formed on each shell, they being arranged so that one is on each

side of one of the cross-bars 8 of the diaphragms as best shown in Fig. 5, whereby 65 each shell is strictly confined in position on its diaphragm and prevented from slipping thereon. On the edge opposite to its hinged edge, each shell has also a narrow, tang-shaped metal extension 10, which serve as 70 catches to hold them down on their diaphragms, the engagement being merely a frictional one, with one of the bars 7, as shown in Fig. 3. This connection of the shells to the diaphragms is shown modified 75 in Fig. 5, where they are secured to the underside of these latter, the engagement being a sliding one. For such purpose the edges of the shells are shown turned outwardly and fitted into guide-ways formed 80 on the diaphragms.

Having described my invention, I claim as new:

1. A nasal inhaler consisting of a flat diaphragm slotted in a manner that bars, substantially parallel, result, there being an outer continuous bar which forms the contacting edge of said diaphragm when in position and a shell supported on this latter of a size sufficiently smaller so as to leave 90 uncovered, said continuous outer bar and also the slotted portions of the diaphragm next to it, to permit passage of air.

2. A nasal inhaler consisting of an orificed receptacle provided with a continuous 95 curb which projects laterally all around it and is shaped to conform to the shape of the nasal passage transversely considered, at the point where the device occupies said passage, and adapted to hold the tissues, 100 surrounding said passage, spaced from the receptacle and out of contact therewith.

3. A nasal inhaler consisting of two flat diaphragms, a spring-bow which connects them, and shells, one hinged connected to 105 one side of each of these diaphragms and forming with them receptacles adapted to contain medicated matter, the walls of these receptacles being multiperforated.

4. A nasal inhaler consisting of two flat 110 diaphragms perforated by slots which are separated by bars, a spring-bow which connects them and multiperforated shells which have tangs projecting from their edges adapted to engage the bars of the diaphragms for adjustable connection of said shells to them.

5. A nasal inhaler consisting of two flat diaphragms perforated by slots which are separated by bars, a spring-bow which connects them, multiperforated shells which have tangs projecting from their edges which are bent around the bars mentioned to form hinges whereby the shells are connected to the diaphragms.

6. A nasal inhaler consisting of two flat,

perforated diaphragms, a spring-bow which connects them and multiperforated shells, one for each diaphragm, they having each two tangs projecting from their edges
5 which are shaped to form hinges and engage the diaphragms, each tang occupying a different perforation.

In testimony whereof, I hereunto affix my signature in the presence of two witnesses.

ALPHONSO RIGGS.
